UNITED STATES PATENT OFFICE

147,424

DESIGN FOR A CHILD'S SLIPPER

John J. Vogl, Milwaukee, Wis., assignor to
Badger Glove and Slipper Company, Milwaukee,
Wis., a corporation of Wisconsin

Application January 17, 1947, Serial No. 136,206

Term of patent 14 years

(Cl. D7—5)

To all whom it may concern:

Be it known that I, John J. Vogl, a citizen of the United States, residing at Milwaukee, in the county of Milwaukee and State of Wisconsin, have invented a new, original, and ornamental Design for a Child's Slipper, of which the following is a specification, reference being had to the accompanying drawing, forming a part thereof, and in which:

Fig. 1 is a front view;

Fig. 2 a top view; and

Fig. 3 a side view of a child's slipper showing my new design.

I claim:

The ornamental design for a child's slipper, substantially as shown.

JOHN J. VOGL.
